UNITED STATES PATENT OFFICE.

PETER J. BERTUCCI, OF NEW YORK, N. Y.

DESIGN FOR A RAZOR-WIPER.

SPECIFICATION forming part of Design No. 26,020, dated September 15, 1896.

Application filed July 21, 1896. Serial No. 600,069. Term of patent 7 years.

To all whom it may concern:

Be it known that I, PETER J. BERTUCCI, a citizen of the United States, residing at New York, in the county of New York and State of New York, have invented and produced a certain new and original Design for a Razor-Wiper; and I do declare the following to be a full, clear, and exact description of the invention, such as will enable others skilled in the art to which it appertains to make and use the same.

The figure in the drawing is a perspective view of a razor-wiper embodying my design.

The essential feature of my design consists in the shape of the handle substantially as

shown, such shape comprising the approximately rectangular handle having a plane and a semicircular end, longitudinally-grooved sides, and projecting ribs extending beyond the parallel plane faces for about one-half the length of the handle.

What I claim is—

The design for a razor-wiper, substantially as herein shown and described.

In testimony whereof I hereunto affix my signature in presence of two witnesses.

PETER J. BERTUCCI.

Witnesses:

MARY ROURKE,

FRANK. BAKER.
